Elisha Johnson, of Rochester New-York

Letters Patent.

The schedules referred to in these Letters Patent, and making part of the same, containing a description in the words of the said Elisha Johnson himself of his improvement, in the construction of Rail Roads.

To all to whom these presents shall come.

Be it known that I, Elisha Johnson, of the village of Rochester, County of Monroe, State of New-York, have invented, & made useful improvement in the plan & form of putting down the timber work in the construction of Rail Roads, which has not heretofore been used or known.

Fig. 1. Represents the improvement claimed, a. a. sleepers of round timber buried in the earth of any size, or round timber buried on one side, or of any other description or form of timber. Fig. 2. Represents the usual form of construction with variations of size and form of timber a. a. longitudinal sill 3 by 6 inches b. b. sleepers or cross timbers 3 feet apart 3 to 7. c. c. rails of yellow or Norway pine 6 by 6 inches prepared in the form represented. d. d. d. Horse path of earth, gravel or rubble, placed in the grading or resting on abutments, trestle work piles, or any other form of support. f. f. plank of two inches in thickness 7 feet in length or of any other length or thickness or of any width, bearing upon the sleepers a. a. a. grading forming a continued floor. g. c. rails or furring to receive the iron plates 3 by 6 inches or of any other size or of any other form or material other than wood to receive the wheels of the cars resting upon a plank flooring c. a. spike plain or rugged to connect the iron and timber work to the sleepers or sill a. or by nuts, pins, or any other form of joining. The aforesaid described materials the flooring to be covered on each in thickness with sand or gravel. — The improvement claimed is the form of fig. 1. combining cheapness of material, simplicity of construction, & ease of putting down for roads, & all other improvements being of timber resting upon the ground by an iron floor.

Planning application issued against the effect of forest as well as
other activities on benefits resulting therefrom. A further plan
corresponding with the above, with applications, filed in the
District Office, August 5, 1920.
